UNITED STATES PATENT OFFICE.

LESLIE E. OPIE, OF CEDAR RAPIDS, IOWA.

MEANS FOR SAVING RADIATOR-OVERFLOW.

1,317,723.

Specification of Letters Patent.

Patented Oct. 7, 1919.

Application filed December 16, 1918. Serial No. 266,960½.

To all whom it may concern:

Be it known that I, LESLIE E. OPIE, a citizen of the United States, residing at Cedar Rapids, in the county of Linn and State of Iowa, have invented certain new and useful Improvements in Means for Saving Radiator-Overflow; and I do hereby declare the following to be a full, clear, and exact description of the invention, such as will enable others skilled in the art to which it appertains to make and use the same.

This invention relates to the radiators of automobile engines, the object of the invention being to conserve the water supply in such radiators by providing means adapted to catch and save the overflow therefrom.

The nature of the invention is fully disclosed in the description and claims following, reference being had to the accompanying drawing, in which:—

Figure 1 is a front elevation of a device embodying my invention as in use. Fig. 2 is a central section of the catch-vessel shown in Fig. 1. Fig. 3 is an elevation of the same as seen from the side. Fig. 4 is a plan view of the same.

In the drawing, the numeral 1 designates an automobile engine radiator of a familiar type. This is provided with the usual overflow pipe 2, which is herein shown terminating in an elbow outlet 3, so as to avoid any kink in the section of hose 4 connecting with it.

At some convenient point, as for example a shelf 5 attached to the main frame 6 of the automobile body, is mounted a vessel 7 to catch the overflow from the radiator. This is here shown as a can, divided vertically by a partition 8, and the separate compartments closed by tight-fitting lids 9 and 10. The former is a close lid, adapted to seal the compartment 11 practically airtight. In this compartment is placed a tube 12 extending to the center of the bottom, and at its upper end formed with an elbow 13 to receive one end of the section of hose above mentioned. The other compartment has a similar tube 14, whose upper end opens into the compartment 11. A vent-hole 15 is made in the lid of this compartment 16. For convenience in attaching the

vessel to its support it is provided with depending ears 17, and by means of wires 18, or the like, the vessel is secured to its supporting shelf. In the vented chamber is placed a small quantity of some non-volatile liquid 19, preferably heavy oil. This very largely arrests any outflow of steam, and practically seals the chamber against the escape of water.

The operation of the device will be evident from the foregoing. An excess of heat and pressure in the radiator will cause the steam and water therein to overflow. If the radiator cap 20 is tight, as it should be, the overflow can only escape into the receiver 7. The closed chamber therein serves to catch the hot water of condensation, any residual steam passing through the tube 14 to the bottom of the chamber 16. Here the steam is further arrested, and further condensation takes place, no water, and very little steam escaping, even under the severest conditions of service. When the heat and pressure subsides in the radiator, assuming it to be properly tight, the contents of the receiver will be nearly all sucked back into the radiator. This serves to keep the radiator properly filled, without attention on the part of the operator, except to add a little water from time to time to compensate for a little waste which cannot be avoided.

The device is useful everywhere, and especially in semi-arid regions, to conserve water at all times. It serves also to cut off much of the cost of up-keep in freezing weather, by arresting the waste of anti-freezing material, of which alcohol is usually regarded as the most practical ingredient.

Having thus described my invention, I claim:

1. A device for arresting waste and evaporation from automobile radiators, comprising a vessel provided with a tube extending from the top to the bottom thereof and a vent near the top, means for connecting the upper end of said tube with the overflow pipe of the radiator, and an arresting medium, such as oil, adapted to float on the water overflowing into said vessel, substantially as described.

2. A waste-arresting device for radiators, comprising a vessel separated into two cham-

bers by a vertical partition, one of such chambers being closed and the other vented, a tube in the closed chamber opening outwardly at or near the top and inwardly near the bottom of said chamber, a tube in the vented chamber opening at the top into the closed chamber, and at the lower end near the bottom of the vented chamber, and a

connection of said first named tube with the overflow pipe of the radiator. 10

In testimony whereof I affix my signature in presence of two witnesses.

LESLIE E. OPIE.
